(57) **CLAIM**

The ornamental design for an automobile body, as shown and described.

DESCRIPTION

FIG. 1 is a front right perspective view of an automobile body constructed according to my novel design;

FIG. 2 is a right side view thereof;

FIG. 3 is a rear right elevational perspective view thereof;

FIG. 4 is a front view thereof;

FIG. 5 is a rear view thereof; and,

FIG. 6 is a top plan view thereof.

The broken lines showing of environmental structure in FIGS. 1-5 of the drawings are for illustrative purposes only and form no part of the claimed design.

A left side view has been omitted because this view is identical to the left view shown in FIG. 2.
